UNITED STATES PATENT OFFICE.

JOHN TITUS METCALFE, OF QUINCY, PENNSYLVANIA.

IGNITER FOR EXPLOSIVE-ENGINES.

SPECIFICATION forming part of Letters Patent No. 691,561, dated January 21, 1902.

Application filed July 25, 1901. Serial No. 69,712. (No model.)

To all whom it may concern:

Be it known that I, JOHN TITUS METCALFE, a citizen of the United States, and a resident of Quincy, in the county of Franklin and 5 State of Pennsylvania, have invented a new and Improved Igniter for Explosive-Engines, of which the following is a full, clear, and exact description.

My invention relates to igniters for exploding the gas in the cylinders of gas and gasoline engines.

My invention further relates more particularly to means producing a distinct and positive spark at a certain period of the rotation 15 of the main shaft, this period being governable at will.

The invention consists of novel features and parts and combinations of the same, as will be fully described hereinafter and then 20 pointed out in the claims.

Reference is to be had to the accompanying drawings forming a part of this specification, in which similar characters of reference indicate corresponding parts in all the views.

25 Figure 1 is a side elevation of my device as applied to a gas-engine. Fig. 2 is a plan view of the same, a certain part of the cylinder being broken away, so as to exhibit the sparking device proper. Figs. 3 and 4 are 30 fragmentary elevations showing some of the same parts as Fig. 1, but in different positions. Fig. 5 is a section on the line 5 5 in Fig. 1 looking in the direction of the arrow, certain details being partly broken away.

35 Fig. 6 is a fragmentary section on the line 6 6 in Fig. 5 looking in the direction of the arrow. Fig. 7 is an enlarged section on the line 7 7 in Fig. 1 looking in the direction of the arrow; and Fig. 8 is a fragmentary elevation 40 of the sparking device proper, another view of which is shown in Fig. 2.

Upon the frame 1 of the engine is secured a cylinder 2, having a cylinder-head 3, which is provided with a central cup or receptacle 45 4, integral therewith, and provided with a screw-cap 5, secured thereto by means of threads 6. This screw-cap 5 is provided with an aperture 7 for establishing communication between the cylinder proper and the space 8 50 inside of the receptacle for the purpose of bringing the explosive gases into communication with the piston. In the space 8 is the

sparking apparatus proper, which is actuated by the mechanism outside of the cylinder. Upon a revoluble shaft 9, which is mounted 55 in a bearing 10, there is a revoluble sleeve 11, provided with a disk 12. By means of heads 13 and 15 a connecting-rod 14 connects a crank-pin 13' with the lower end of a rocking lever 16, so that the revolution of the shaft 60 9 causes a rocking of the lever 16. This lever 16 is loosely pivoted at its center upon a shaft 24, which has a slight rocking movement independent of the rocking movement of the lever 16, as will be hereinafter explained. The lever 16 is free to move upon its shaft independently of its rocking movement. Upon the upper end of the rocking lever is loosely secured, by means of a head 17, a catch 18, which moves back and forth 65 as the lever is rocked. Upon the shaft 24 is loosely pivoted a heavy arm 19, which is connected with the shaft 24 by means of a spiral spring 21. This heavy arm 19 when actuated by the spring acts as a hammer and by 70 the rocking of the lever is pulled or tilted back by means of the catch 18 and suddenly released, so as to strike a blow under tension of the spring. This heavy arm, which I term a "hammer," is normally pressed by the 75 spring 21 into engagement with the anvil face or lug 20, which is secured, by means of a bolt 42, upon the shaft 24—that is to say, a member consisting of two spring-arms 41 and the anvil or lug 20 is loosely fitted upon the 80 shaft 24 and tightened, by means of the bolt 42, so as to become relatively fixed to said shaft 24, and the hammer, which is wide at its top, normally engages the anvil-surface mentioned. When the lever rocks, the catch 85 18 engages the hammer 19, holds the same backward contrary to the tension of the spring 21, and then releases said hammer, which strikes a quick blow upon the anvil-face of the lug 20.

In order to effect the release of the hammer 95 19 more readily and to make the point of release adjustable at will, an arm 40 is mounted upon the same shaft as the catch 18 and is normally rigid therewith, so that the rocking of the arm 40 causes the catch 18 to rock. This arm 40 is engaged by a boss 26 upon a head 24', which is integral with the lower end 100 of the base of the hand-lever 23, as shown in

Figs. 4 and 6, so that when said hand-lever is moved in an arc the boss is likewise moved radially and is made to govern the movements of the catch 18—that is to say, when 5 the arm 40 engages the boss 26 in its extreme right-hand position, as shown in Fig. 1, the catch 18 releases the hammer 19 at a slightly different period than would be the case if the boss 26 were in its extreme left-hand position 10, being moved to the same by the hand-lever 23. It will be observed, therefore, that this boss (by merely shifting the lever 23 to the right or the left to govern the period when the catch 18) will engage and release the 15 hammer 19, the period of such engagement and release being relative to the period of revolution of the main shaft 9. In other words, the exact moment of the stroke of the 20 shaft 9 can be regulated within certain limits by adjusting the lever 23 to the right or the left, as desired. Upon the other end of the shaft 24 is rigidly secured an arm 37 of conducting material and provided with a platinum contact-point 36, which engages a similar platinum contact-point 35, fixed upon an electrode 34. The points 35 and 36 constitute the make-and-break mechanism for producing sparks in the receptacle 8.

30 Referring now to the action of the hammer 19 when retracted and released by the catch 18, it will be observed that the shaft 24 rocks back and forth, but when released suddenly moves with a snap. This rocking motion 35 causes the arm 37 to be slowly lowered until the platinum contact-point 36 rests upon the platinum contact-point 35, thereby closing the circuit, and then when the hammer 19 is released and flies downward, striking the lug 40, the arm 24 is moved quickly and positively, so as to raise the arm 37 and break the contact between the two platinum points. The 45 result is that the hammer 19 in moving in one direction has a slow motion while in moving in the opposite direction it has a vigorous snap, and the arm 37 is slowly moved until the platinum points are in contact and then is abruptly drawn away, so as to break the contact with a sudden snap. The object of 50 this movement is to facilitate the breaking of the contact between the points 35 and 36 for the purpose of making the spark abrupt and positive in its action. When the spark ignites the gases, an explosion takes place, as 55 in any other engine, and need not be further described.

It is now obvious, since the adjusting-lever 23 can be so used as to govern the period when the spark is made relative to the position 60 of the main shaft, that the spark can be made at any desired point within reasonable limits relatively to the stroke of the engine. When the adjusting-lever is in the center of the guard 22, the spark is produced while the 65 engine is on a dead-center. If the lever be moved to the right, as shown in Fig. 1, the spark is produced just before the engine

moves on its dead-center. If the lever be moved to the left, the spark will be produced immediately after the engine leaves its dead-center. This being the case it is obvious that by means of the adjusting-lever 23 the explosion can be made to take place just before or just after the dead-center is passed and can therefore be made to reverse the direction 75 of the engine. In this connection it should be remembered that the means for reversing the direction of the piston in a gas-engine can be very simple. If the spark be made just before the engine reaches the dead-center, the 80 engine going ahead in the usual direction, the effect will be a reversal of motion in the engine, whereas if the spark be made just after the engine passes the dead-center, supposing the engine to be in the usual position 85 going ahead, the effect will be to drive it ahead in the usual manner, so that by merely adjusting the period when the spark is made relatively to the position of the piston as regards the dead-center, or, what is substantially the same thing, as regards the position 90 of the main shaft, the engine can be driven ahead or backward, as desired.

In my device I inclose the contact-points for the sparking apparatus proper in the receptacle shown in Fig. 2, so as to protect these parts from the violence of the explosion—that is to say, the gases are ignited inside of this receptacle, and the local explosion causes the general explosion to take place in the cylinder proper, the communication being established through the aperture 7. To be sure, the sparking device proper is subject to slight violence of the local explosion in the receptacle, yet the casing comprising the cap 5 and the wall 4 prevents the explosion from damaging the parts as much as would be the case if they were thoroughly exposed to the cylinder. Besides, by means of this receptacle the explosive gases within the narrow space 105 8 can be much better mixed and otherwise better prepared for explosion than would be the case if the sparking device were thoroughly exposed within the end of the cylinder. 115

The electrical connections other than as above described are as follows: The wires 27 28 are connected to any source of electricity, as is usual with other devices of this kind. These wires are secured by binding-nuts 29 30 upon bolts 29' 30'. The bolt 30 is secured directly to the metallic disk 25, while the bolt 29' is insulated from this disk by the asbestos packings 31 32 and the insulating-washers 33, which may be of porcelain. The bolt 29' and the shaft 24 are therefore insulated from each other throughout, except when the arm 37 is lowered so as to make contact between the platinum points 35 36. 125

Having thus fully described my invention, I claim as new and desire to secure by Letters Patent—

1. An igniter for explosive-engines, comprising an electric circuit provided with sepa-

5 rable contacts for producing sparks, a rock-
ing shaft for actuating one of said contacts,
a lug rigidly mounted upon said rocking shaft
and provided with an anvil-face, a spring-
driven hammer loosely mounted upon said
rocking shaft and free to strike said anvil-
face, a rocking lever loosely journaled on
said rocking shaft, a catch mounted upon said
rocking lever for engaging said hammer, and
10 a movable arm for releasing said catch.

2. An igniter for explosive-engines, com-
prising an electric circuit provided with sepa-
rable contacts for producing sparks, a rock-
ing shaft for actuating one of said contacts,
15 a lug rigidly mounted upon said rocking shaft
and provided with an anvil-face, a spring-
driven hammer loosely mounted upon said
rocking shaft and free to strike said anvil-
face, a rocking lever loosely journaled on
20 said rocking shaft, a catch mounted upon said
rocking lever for engaging said hammer, a
movable arm for releasing said catch, and a
pivotally-mounted hand-lever provided with
a boss for controlling said arm.

3. An igniter for explosive-engines, com- 25
prising an electric circuit provided with sepa-
rable contacts for producing sparks, a rock-
ing shaft for actuating one of said contacts,
a lug provided with an anvil-face and with
spring members for engaging a rocking shaft, 30
a spring-driven hammer for striking said lug,
a catch for periodically engaging said ham-
mer, means for periodically actuating said
catch, a movable arm for disengaging said
catch from said hammer, and an adjusting- 35
lever mounted upon a pivotal support and pro-
vided with a boss disposed eccentrically to the
said pivotal support for the purpose of con-
trolling the disengagement of said catch from
said hammer. 40

In testimony whereof I have signed my
name to this specification in the presence of
two subscribing witnesses.
